Primary Examiner — Susan Bennett Hattan*Assistant Examiner* — Rebecca Tsehay(74) *Attorney, Agent, or Firm* — Dentons US LLP(57) **CLAIM**

The ornamental design for an artificial eyelash extension applicator, as shown and described.

DESCRIPTION

FIG. 1 is an illustration of a front perspective view of another embodiment of an artificial eyelash extension applicator;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof;

FIG. 7 is a bottom view thereof; and,

FIG. 8 is a bottom perspective view thereof.

The broken lines shown in the drawings illustrate portions of the applicator that form no part of the claimed design.

1 Claim, 5 Drawing Sheets(56)
